FIG. 5.

ALBERT N. MENSER Inventor

By Bernard J. Farley

Attorney

UNITED STATES PATENT OFFICE.

ALBERT N. MENSER, OF JOHNSTOWN, PENNSYLVANIA, ASSIGNOR OF ONE-HALF TO
JOSEPH MOORE, OF JOHNSTOWN, PENNSYLVANIA.

RAIL-FASTENER.

1,378,366.

Specification of Letters Patent. Patented May 17, 1921.

Application filed February 24, 1921. Serial No. 447,440.

To all whom it may concern:

Be it known that I, ALBERT N. MENSER, a citizen of the United States, residing at Johnstown, in the county of Cambria and 5 State of Pennsylvania, have invented certain new and useful Improvements in Rail-Fasteners, of which the following is a specification.

The present invention relates to rail fasteners, and has for an object the production 10 of a device of simple construction which will effectively hold the rail on the tie.

Another object of the invention is to provide a fastener, the inherent construction of 15 which enables it to be connected directly to the tie thereby eliminating possibility of lateral thrust of the rail even though the rail spikes should be displaced.

The above and other objects of this invention will be in part described and in part 20 understood from the following description of the present preferred embodiment of the invention taken in connection with the accompanying drawings, wherein:

25 Figure 1 is a top plan view of a device constructed in accordance with this invention illustrating its application.

Fig. 2 is a transverse sectional view 30 through the rail, illustrating the application of my invention.

Fig. 3 is a perspective view of the fastener *per se*.

Fig. 4 is a vertical sectional view taken 35 on the line 4-4 of Fig. 2, looking in the direction of the arrow, and

Fig. 5 is a plan view of the fastener in blank.

In the drawings in order to illustrate the application of this invention, portions of 40 ties are shown which have mounted thereon a portion of a standard type of rail. The rail is provided with base flanges 8 of the usual construction.

The fastener consists of a metal sheet 9 45 preferably of a rectangular configuration and has one of its margins extended to provide a tooth 10. One marginal edge of the tooth 10 is straight and extends into the body of the blank by incising the latter as indicated at 11. The opposite margin of the tooth tapers. Consequently, the fastener may be first stamped from a sheet of metal in a manner well known in the art.

After the blank 9 has been stamped, the

tooth 10 is bent downwardly at right angles 55 and has the terminal thereof bent inwardly so as to lie parallel with the body of the blank as shown to advantage in Fig. 3. The body of the blank, beyond the incision 11, is pressed upwardly so as to lie at an angle 60 complementing the base flange 8 of the rail.

In use of this device, after the rail has been placed on the tie, one of the fasteners is engaged with the tie at one side of the rail, and another fastener engaged with the tie at the opposite side of the rail. The fasteners are engaged by first driving the teeth 10 into the lateral faces of the tie, after which spikes 13 are driven through apertures 14 formed in the blanks. Preferably, the plates are arranged as shown in Figs. 1 and 2 of the drawings, which show the tooth of one plate engaged with one of the lateral faces of the tie and the tooth of the other plate engaged with the opposite 75 face of the same tie. In this way, a more positive purchase of the plate will be effected. When the plates are positioned in this way, the bodies of the plates will be superimposed on the base flanges 8, and the margins of the blanks engaged with the upper faces of the ties. The heads of the spikes will overlap the bodies of the blanks and also the base flanges 8.

Various changes may be made in this invention especially in the construction of the plates and their manner of application to the ties and rails. Various other changes may be made within the scope of the appended claims.

90 What is claimed is:

1. In combination with a rail and tie, a rail fastener including a plate engaged with the top of the tie which has a portion thereof arched upwardly to embrace the base 95 flange of the rail, a portion of one terminal of the plate being extended and tapered to a point for flexure over the top of the tie and penetration in the side of the latter.

2. In combination with a rail and tie, a 100 rail fastener including a pair of plates, a portion of each of which is engaged with and extends completely across the top of the tie and embraces the base flange of the rail, both plates having portions thereof embedded in the lateral faces of the tie.

ALBERT N. MENSER.
